LIPSTICK HOLDER

Philip A. Reutter, Waterbury, Conn., assignor to
Scovill Manufacturing Company, Waterbury,
Conn., a corporation of Connecticut

Application September 20, 1934, Serial No. 744,749

9 Claims. (Cl. 206—56)

This invention relates to lipstick holders.

It is the principal object of the invention to provide an improved lipstick holder that is simple in construction and economical to manufacture.

With these general objects and others in view, the invention consists in the features, combinations, details of construction and arrangements of parts which will first be described in connection with the accompanying drawing and then more particularly pointed out.

In the drawing:

Fig. 1 is a view in front elevation of a lipstick holder constructed in accordance with the invention;

Fig. 2 is a sectional view taken on the line 2—2 of Fig. 1;

Fig. 3 is a similar view showing the holder open and the stick advanced for use;

Fig. 4 is a sectional view (enlarged) taken on the line 4—4 of Fig. 2 but showing a slight modification;

Figs. 5 and 6 are perspective views of parts removed;

Fig. 7 is a fragmentary view similar to part of Fig. 2, showing a modification;

Fig. 8 is a fragmentary perspective view, showing a modified form of the part shown in Fig. 5; and

Fig. 9 is a view similar to Fig. 4 but embodying the modification of Fig. 8.

Referring to the drawing, and more particularly to Figs. 1—6, the embodiment of the invention here illustrated as an example includes a casing 21 rectangular in cross section and open at the lower end. The upper end of the casing is rounded and is cut out to form an opening 22 for the lipstick 23. The lipstick is mounted in a cup-like carrier 24 having a vertical movement in the holder.

The invention in its entirety includes an actuating unit comprising a thumb-piece and a flexible strip connecting the latter with the carrier, part of the strip serving as a closure for opening 22. As here shown as an example, movable within the casing and guided as later described, is a flexible strip 25. In carrying out the invention to what is now considered the best advantage, this strip is formed of a non-metallic substance, for example, a plastic material such as the plastic cellulose acetate compound commonly marketed under the name "Plastecel". One end of flexible strip 25 is connected to the carrier 26. At some distance from its other end, the strip is riveted to an actuating thumb-

piece 28. This thumb-piece operates in a slot 29 formed in the front wall of casing 21.

The invention in its entirety includes an insert or liner capacitated to be formed from a flat stamping and providing guiding means for the flexible strip and a closure for slot 29. In the embodiment illustrated as an example in Figs. 1—5, the liner comprises parallel side walls 31, 32, rounded at their ends as appears more clearly in Fig. 5. These side walls are connected by an integral front wall 33 which terminates just short of the rounded ends of the side wall (Figs. 2, 3). The rear of the liner is provided with a longitudinal opening for the passage of rivet 26. In the present exemplification this end is attained by omitting a rear wall entirely, the opening being the space between side walls 31, 32 (Figs. 4, 5).

The flexible strip 25 moves between the casing wall and front wall 33 of the liner. If desired, the wall 33 may be dished inwardly to reduce the bearing surface for the strip, as indicated at 35 (Fig. 4).

The upper end of each side wall of the liner, at its rear edge, is formed with a lug 36. The outer face of each side wall has a nib 37. These lugs and nibs serve to centralize or position the liner in the casing so as to attain and maintain the proper spacing for free movement of the flexible strip.

In closed position of the holder (Figs. 1 and 2), the thumb-piece 28 is at the top of slot 29 and the free end of flexible strip covers opening 22, thus closing the upper end of the holder. In order to use the lipstick, the thumb-piece is moved down the slot. The consequent movement of the flexible strip 25 advances the carrier upwards in the holder. At the same time, the free end of the strip is withdrawn into the holder so that by the time the advancing end of the lipstick reaches the top of the holder, opening 22 has been uncovered. This permits continued movement of the thumb-piece to project the lipstick to a position for use (Fig. 3). Reverse movement of the thumb-piece returns the parts to initial position.

During these movements, the flexible strip 25 is guided at the front by the casing and the front wall 33 of the liner. At the upper end, the strip is guided between the round top of the casing and the rounded ends of the liner side walls. At the lower end, the strip is guided between the rounded ends of the liner side walls and a part hereinafter referred to.

As appears more clearly in Figs 3 and 4, the

front wall 33 of the liner serves as a closure for slot 29, in all positions of the actuating unit, to prevent dust and dirt from getting into the cosmetic stick.

5 It will be apparent that the liner described can be economically formed from a flat stamping, the side walls 31, 32, being bent up to the form shown.

The invention in its entirety includes a closure 10 for the open lower end of the casing and means for anchoring closure and liner together by the mere act of assembly. As here shown as an example, the closure comprises a U-shaped insert comprising a bottom closure plate 40 and side plates 41. Each side plate 41 has two holes 42 for taking over pin-like nibs 43 on the liner side wall, formed by striking up the metal thereof. During assembly, the side plates 41 spring 15 sufficiently to enable the holes 42 to be passed over pins 43, whereupon closure and liner are automatically anchored together, thus positioning the liner in the casing.

The invention in its entirety includes means 20 for anchoring the unit, comprising the liner and end closure, in the casing by the simple act of assembly. As here shown as an example, the side plate 41 of the end closure has a half-moon hole 45. Struck in from the side wall of the casing is a corresponding nib (not shown). When 25 the assembled liner and end closure are inserted in the casing, the nib snaps into hole 45 and anchors the unit in the casing. For convenience, each side plate 41 is provided with a hole 45 so the end closure can be assembled indiffer- 30 ently faced.

There is provided a guiding element for the 35 lower end of the holder for cooperating with rounded ends of the liner side walls. As here illustrated as an example, this guiding element 40 comprises an arc-shaped plate 46 having, at each end, a supporting leg 47. This guiding element is supported on the inner face of closure plate 40. It is positioned transversely by side plates 41 and longitudinally, once assembled, by the 45 casing (Fig. 3).

With the construction described, the bottom closure is secured in the casing and the proper 50 relative position of the liner in the casing is attained and maintained. Moreover, this end is accomplished by the simple act of assembly and the closure and liner can, if desired, be removed for inspection, repairs and the like.

Fig. 7 illustrates a modification embodying a 55 different method of connecting the flexible strip with the carrier cup 24, but otherwise identical. Rivet 26 is omitted and the end of the strip has secured thereto, as by riveting, a simple pin 55. This pin takes into a suitable hole in the carrier cup. This construction simplifies assembly 60 in that the parts are connected simply by inserting pin 55 in the carrier. Once the parts are assembled in the casing, pin 55 is prevented from withdrawing by the adjacent wall of the casing.

Figs. 8 and 9 illustrate a modified form of 65 liner. As there shown, the liner comprises side walls 48, 49, like side walls 31, 32, and a front wall 50 like front wall 33, except that the dished arrangement is omitted. At the rear are in- 70 turned flanges 51 forming, in effect, a rear wall having a vertical slot 52 for the passage of rivet 26 or pin 55, whichever form is used. At the upper end, each flange 51 has a positioning nib 53. This liner, like the one first described, is 75 conveniently formed from a flat stamping.

What is claimed is:

1. In a lipstick holder, and in combination, a 5 casing having a rounded top cut away to form an end opening, a three-sided liner in the casing comprising two side walls having rounded ends and an integral connecting wall terminating short of the rounded ends of the side walls, a carrier for a lipstick movable within the liner, and an actuating unit connected with the carrier comprising a thumb-piece operating in a slot 10 formed in the casing and a flexible strip guided between the casing and the liner, the upper free end of the strip serving to cover and uncover said end opening as the strip is moved.

2. In a lipstick holder, and in combination, a 15 casing open at its lower end and having a rounded top cut away to form an end opening, a liner in the casing comprising two side walls having rounded ends and an integral connecting wall terminating short of the rounded ends of 20 the side walls, a carrier for a lipstick movable within the liner, an actuating unit connected with the carrier comprising a thumb-piece operating in a slot formed in the casing and a flexible strip guided between the casing and the 25 liner, the upper free end of the strip serving to cover and uncover said end opening as the strip is moved, and a closure for the lower end of the casing comprising an end plate and two side plates telescoping within the casing, said side 30 plates being substantially entirely within the casing when the parts are assembled, whereby the bottom plate of the closure substantially abuts the end of the casing to close the same.

3. In a lipstick holder, and in combination, a 35 casing open at its lower end and having a rounded top cut away to form an end opening, a liner in the casing comprising two side walls having rounded ends and an integral connecting wall terminating short of the rounded ends of 40 the side walls, a carrier for a lipstick movable within the liner, an actuating unit connected with the carrier comprising a thumb-piece operating in a slot formed in the casing and a flexible strip guided between the casing and the 45 liner, the upper free end of the strip serving to cover and uncover said end opening as the strip is moved, a closure for the lower end of the casing comprising an end plate and two side plates telescoping within the casing, said side 50 plates being substantially entirely within the casing when the parts are assembled, whereby the bottom plate of the closure substantially abuts the end of the casing to close the same, and means for automatically securing said liner 55 and end closure in definite spaced relation upon assembly thereof in such relation.

4. In a lipstick holder, and in combination, a 60 casing open at its lower end and having a rounded top cut away to form an end opening, a liner in the casing comprising two side walls having rounded ends and an integral connecting wall terminating short of the rounded ends of the side walls, a carrier for a lipstick movable within the liner, an actuating unit connected 65 with the carrier comprising a thumb-piece operating in a slot formed in the casing and a flexible strip guided between the casing and the liner, the upper free end of the strip serving to cover and uncover said end opening as the strip 70 is moved, and a closure for the lower end of the casing comprising an end plate and two side plates telescoping within the casing, said side 75 plates being substantially entirely within the casing when the parts are assembled, whereby 80

the bottom plate of the closure substantially abuts the end of the casing to close the same, said end closure and liner having the one a nib and the other a hole for receiving the nib, whereby the end closure and liner are secured together in definite spaced relation upon assembly in such relation.

5. In a lipstick holder, and in combination, a casing open at its lower end and having a 10 rounded top cut away to form an end opening, a liner in the casing comprising two side walls having rounded ends and an integral connecting wall terminating short of the rounded ends of the side walls, a carrier for a lipstick movable 15 within the liner, an actuating unit connected with the carrier comprising a thumb-piece operating in a slot formed in the casing, and a flexible strip guided between the casing and the liner, the upper free end of the strip serving to 20 cover and uncover said end opening as the strip is moved, a closure for the lower end of the casing comprising an end plate and two side plates telescoping within the casing, said side plates being substantially entirely within the 25 casing when the parts are assembled, whereby the bottom plate of the closure substantially abuts the end of the casing to close the same, means for automatically securing said liner and end closure in definite spaced relation upon assembly thereof in such relation, and means for 30 automatically securing the unit comprising the liner and end closure within the casing upon insertion thereof in the casing.

6. In a lipstick holder, and in combination, a casing open at its lower end and having a 35 rounded top cut away to form an end opening, a liner in the casing comprising two side walls having rounded ends and an integral connecting wall terminating short of the rounded ends of the side walls, a carrier for a lipstick movable 40 within the liner, an actuating unit connected with the carrier comprising a thumb-piece operating in a slot formed in the casing and a flexible strip guided between the casing and the liner, the upper free end of the strip serving to 45 cover and uncover said end opening as the strip is moved, a closure for the lower end of the casing comprising an end plate and two side plates telescoping within the casing, said side plates being substantially entirely within the 50 casing when the parts are assembled, whereby the bottom plate of the closure substantially abuts the end of the casing to close the same, and means for automatically securing said liner and end closure in definite spaced relation upon assembly thereof in such relation, said end closure and casing having the one a nib and the other a hole for receiving the nib, whereby the unit comprising the end closure 55

and casing is automatically anchored in the casing upon insertion therein.

7. In a lipstick holder, and in combination, a casing having a rounded top cut away to form an end opening, a liner in the casing comprising two side walls having rounded ends and an integral front wall terminating short of the rounded ends of the said walls, the rear of said liner having a longitudinal opening, a carrier for a lipstick movable in the liner, a flexible strip 10 guided between the casing and the liner and connected adjacent one end with said carrier, said longitudinal opening serving as a passage for said connection, and an actuating thumb-piece connected with the flexible strip at a distance from its other end, the casing having a slot for said thumb-piece, said slot being backed by said front wall of the liner, the free end of the flexible strip serving to cover and uncover said end opening as the strip is moved. 15

8. In a lipstick holder, and in combination, a casing open at its lower end and having a rounded top cut away to form an end opening, a liner in the casing comprising two side walls having rounded ends and an integral connecting wall terminating short of the rounded ends of the side walls, a closure for the lower end of the casing comprising an end plate and two side plates telescoping within the casing, an arcuate 20 guiding element having supporting legs and located in the channel of said end closure, a carrier for a lipstick movable within the liner, and an actuating unit connected with the carrier and comprising a thumb-piece operating in a slot formed in the casing and a flexible strip, the 25 upper free end of the flexible strip serving to cover and uncover said end opening as the strip moves, the strip being guided at the upper end of the holder between the rounded top of the casing and the rounded ends of said liner side 30 walls and at the lower end between the rounded ends of the liner side walls and said guiding element. 35

9. In a lipstick holder, and in combination, a casing having a rounded top cut away to form an 40 end opening, a three sided liner in the casing capacitated to be formed from a unitary flat blank and comprising two side walls having rounded ends and an integral connecting wall terminating short of the rounded ends of the 45 side walls, a carrier for a lipstick movable within the liner, and an actuating unit connected with the carrier comprising a thumb-piece operating in a slot formed in the casing and a flexible strip guided between the casing and the liner, the 50 upper free end of the strip serving to cover and uncover said end opening as the strip is moved. 55
